CLAIM

The ornamental design for a “convertible napping and changing bag”, as shown and described.

DESCRIPTION

FIG. 1 is a perspective view of a convertible napping and changing bag, showing my new design in an open configuration with a zipper in the process of being closed;

FIG. 2A is a top plan view of one half of the bag in its fully open configuration;

FIG. 2B is a top plan view of the other half of the bag in its fully open configuration;

FIG. 3 is a front elevational view of the bag in its closed configuration;

FIG. 4 is a rear elevational view thereof;

FIG. 5 is a left side elevation view thereof, the right side elevation view being a mirror image thereof;

FIG. 6 is a top plan view thereof; and,

FIG. 7 is a bottom plan view thereof.
